CENTERLESS GRINDING DEVICE

Frank J. Stevens, Nutley, N. J.

Application June 11, 1948, Serial No. 32,434

6 Claims. (CL. 51—108)

1

This invention relates to an improvement in a centerless grinding device and more particularly to a type thereof arranged to operate on insulator bodies.

An object of the present invention is the provision of an improved centerless grinding device wherein cylindrical blanks may be fed continuously to the action of a cutting means for gradually and progressively profiling the cylindrical blanks.

Another object of the invention is the provision, in a centerless grinding device, of a work support having associated therewith a work contacting means to control the movement of the work pieces through the support.

A further object of the invention is the provision of an improved centerless grinding device wherein a cutting or grinding means is arranged eccentrically with respect to the path of work pieces so as to progressively profile the work pieces.

The above and numerous other objects of the invention will become apparent from the succeeding description considered together with the accompanying drawings, wherein:

Figure 1 is a plan view of an improved centerless grinding device embodying the present invention.

Figure 2 is a front elevational view of the improved centerless grinding device shown in Figure 1.

Figure 3 is a vertical sectional view taken along the lines 3—3 of Figure 2, looking in the direction of the arrows.

Figure 4 is a sectional view taken along the lines 4—4 of Figure 3, looking in the direction of the arrows.

Figure 5 is an end elevational view of a cylindrical blank typical of a work piece which may be profiled by the device of the present invention.

Figure 6 is an end elevational view of a profiled work piece after its discharge from the device and illustrative of the profiling which may be effected by the device.

Referring now in detail to the drawings, wherein like reference characters indicate like parts, the numeral 1 is employed to designate, in a somewhat general manner, a centerless grinding device characteristic of the present invention. The centerless grinding device comprises a bed plate or platform 2 which, if desired, may have at its corners the usual standards, legs or supports 3 to maintain the platform in an elevated position or, as will be understood, the bed

2

plate may be placed on a suitable foundation so as to maintain it in a fixed position. Mounted upon the bed plate is a slide or auxiliary mounting plate 4 provided with suitable kerfs to accommodate keys 5 forming a part of the platform and thus the auxiliary mounting plate is interlocked with the bed plate however arranged to move longitudinally relative thereto for the purpose to be made hereinafter apparent. The slide has, at one end thereof, an upstanding apertured wall 6 which may, as desired, be made integral therewith by any means or method so long as it becomes a part of the slide.

Mounted upon what may be termed the inside face 7 of the slide wall is a work piece support or guide ring 8. This guide ring, of curved or annular formation, may be secured to the slide wall by any means (none shown) so long as it is made removable since the illustrated guide ring is only characteristic of a type which may be used depending entirely upon the type of work pieces used and the particular profiling desired. The work piece support has at its upper limits or in proximity thereto a feed or delivery chute 9 which is in the nature of a tubular member communicating with the interior of the work piece support. A hopper or any such means (not shown) may be associated with the delivery chute to feed or supply a continuous stream of work pieces 10 to the delivery chute and the latter is made of such configuration in section in order to accommodate a series of superimposed work pieces. As previously indicated, the work pieces used with the present structure are characterized by the cylindrical blank 11 shown in Figure 5 of the drawings and this blank is preferably made of ceramic material. The blank pieces are preferably formed by the extrusion process or any other method well known or commonly used by the ceramic industry. Also it may be well to state here that the completed component or work piece 12 illustrated in Figure 6 of the drawing has been profiled as desired with a kerf or groove 13 formed in the periphery thereof to adapt the grooved blank to be used as an insulator or bushing.

The support or guide ring, stationary with respect to the slide, is of substantially channel shape in cross section as clearly illustrated in Figure 4 of the drawings and as such functions as a raceway for the accommodation of a continuous flow of blanks therethrough. The guide ring comprises a back-up or circular bearing wall 14 having at one edge thereof an inwardly directed confining flange 15 terminating in a

reentrant flange 16 which is parallel with and spaced a predetermined distance from its companion bearing wall. The other edge of the back-up wall merges with a short, circular retaining flange 17 which is parallel with but shorter than its companion confining flange 15. The distance between the flanges 15 and 17 and the distance between the wall 14 and flange 16 are such as to neatly accommodate and confine the blank 11 and allow the latter to progress in a true path along a given course within the support. As will be noted the bearing wall is provided with an opening as at 18 to allow the blanks entrance to the support as clearly illustrated in Figure 3 of the drawings. It is to be further noted that while the feed chute is illustrated at the top of the stationary support, the relationship between the flanges 16 and 17 is such that the blanks will bridge the distance therebetween and thus prevent the blanks moving other than in the predetermined course in the support.

Substantially diagonally disposed from the feed chute is a discharge chute 19 formed by a tangential extension of the circular bearing wall at 20 (see Figure 3). This arrangement 20 of the bearing wall presents an opening 21 in the support so that as the worked pieces enter this opening they are then free to roll out of the confines of the support to a container (not shown) disposed in a receiving position below the discharge chute. For the extent of the opening 21 the flanges 15 and 17 are extended downwardly to present sides 22 of the discharge chute.

In order to control not only the flow of blanks into the stationary support but also to control the movement of the blanks from the feed chute to the discharge chute there is associated with the stationary support, a cage or holding means 23 formed by a disc 24 having outstanding normally therefrom a plurality of equally spaced pins, fingers or studs 25. The studs are such that they extend into the stationary support through the short retaining flange side thereof and since the disc is arranged to rotate about an axis coincident with the center of curvature of the support the pins will maintain at all times a constant relation with the wall and flanges of the stationary support. As will be noted from the drawings, the blanks are stacked above one another in the feed chute and as the disc rotates in a clockwise direction as viewed in Figure 3, a single blank 11a will drop into the stationary support between adjacent fingers and the next upper blank 11b will be retained in the feed chute until the space between the next adjacent fingers reaches a point beneath the feed chute and then blank 11b will drop thereinto. Thus a continuous and controlled flow of blanks enter the stationary support to be worked on as hereinafter described. Some control must be provided for the disc and toward the accomplishment of this function the slide, off to one side of the disc, has mounted thereon an electric driven motor 26 having mounted on a shaft thereof a double pulley 27. Positioned adjacent to the motor is a box 28 containing a set of reduction gearing (not shown) with dual or oppositely disposed shafts 29 and 30 extending therefrom. The shaft 30 is provided with a double pulley 31 which is in alignment with the motor pulley 27 and the motor and gearing pulleys are connected by an endless belt 32. Thus force is transmitted from the motor to the reduction gearing. The purpose of the double pulleys is obvious, in that since the motor employed is of constant speed the belt may

be aligned or associated with pulleys to develop a required speed of the shaft 29. The disc has, extending axially therefrom, a hub 33 sleeved over the gearing shaft 29 and removably secured thereto so that the disc will move or rotate in response to the action of the gearing shaft 29.

The profiling means for cutting or grinding the blanks is characterized by a wheel 34 which is of such a diameter to enter the confines of the stationary support through its aperture. Any suitable type of grinding wheel may be used or a plurality of spaced wheels may be housed within the support depending entirely upon the profiling design desired.

The grinding wheel is so disposed within the confines of the stationary support that its axis is spaced slightly from the axis of the disc or, in other words, the grinding wheel forms what may be termed an eccentric pattern with respect to the cage fingers or the stationary support. Because of this arrangement the periphery or outer surface of the grinding wheel gradually approaches the back-up wall 14 of the stationary support. Since the distance between the grinding wheel and back-up wall gradually diminishes between the location of the feed chute and location of the discharge chute the grinding wheel is therefore arranged to cut into the blanks as they progress between these two locations so that as the blanks pass the approximate point or station marked 11c in Figure 3 the profiling or grinding operation is completed. Further it will be noted that as a blank such as 11a enters the stationary support it is held out of contact with the grinding wheel and it is not until the blank 11a reaches the station 11d that the blank is contacted by the grinding wheel. At this station 11d the blank is also in contact with the back-up wall 14 of the stationary support and profiling of the blank 30 starts and is completed when the blank reaches the approximate position of the station 11c. By way of a more specific example in devices now in use embodying the present invention the cage is arranged to rotate at a speed of five revolutions per minute and the grinding wheel is arranged to rotate in the same direction at a rate of approximately thirty-six hundred revolutions per minute. It is believed that the frictional value of the line contacts between the fingers and blanks 40 and the back-up wall and blanks is less than the force of the contact between grinding wheel and blank and therefore while the cage acts as a retarding medium the grinding wheel completely profiles the blanks approximately between the stations 11d and 11c.

Since the grinding wheel is fixed longitudinally of the platform the slide is made adjustable longitudinally of the platform so that not only may the grinding wheel be withdrawn from the support 60 to change the wheel after it has worn beyond a permissible degree but also to position the grinding wheel longitudinally of the device so that the profiling of the blanks may be located as desired. Toward the accomplishment of this function one 65 end of the bed plate is provided with an upstanding barrier 35 which has journaled therein a rotatable screw 36 arranged to be manipulated by a hand wheel 37. The screw extends longitudinally of the device through a suitable block 38 forming a part of the slide and because of this arrangement any manipulation of the hand wheel 70 will move the slide axially of and relative to the grinding wheel.

The grinding wheel is mounted on a shaft 39 of 75 a suitable electric motor 40 and as viewed par-

ticularly in Figure 3 of the drawing also rotates in the same direction as the cage, namely, clockwise. Functioning as a carrier for the grinding wheel motor is an inverted channel section 41 having the motor 40 securely anchored thereto intermediate the ends thereof. Disposed immediately beneath the motor carrier is a similar channel section or movable or slidable rest 42 which bears somewhat freely upon the platform and is therefore movable or shiftable relative thereto as will be clearly brought out hereinafter. Upstanding from what may be termed the rear extremity of the slidable rest is a pair of spaced posts 43 firmly anchored to the slidable rest and carrying adjacent their upper extremities a journal or connecting bar 44. The connecting bar extends through suitable apertures in the motor carrier and thus the latter is pivotally connected to the slidable rest and arranged to be pivoted vertically about a horizontal axis. Removed from the pivotal connection last referred to is an adjusting screw 45 having a threaded interlocking relation with the motor carrier. This screw has one end abutting the subjacent slidable rest and its upper end supplied with an operating wheel 46 so that upon a proper manipulation of this last named operating wheel the motor carrier will be pivoted about its journal and the grinding wheel will be moved vertically to accomplish the particular cut or profiling desired. When the grinding wheel becomes worn or if the depth of cut need be corrected a proper manipulation of operating wheel 46 will set the grinding wheel at a proper or desired location.

A third adjustment is believed necessary in the device to properly position the grinding wheel and compensate for wear which is inevitable in a grinding wheel. This third adjustment should move the grinding wheel transversely of the device and accordingly the bed plate is provided with a pair of parallel or longitudinally spaced keys or shoulders 47. These keys occupy neatly, suitable grooves 48 in the slidable rest to thereby arrange for the guidance of the slidable rest and its carried components transversely of the bed plate. Disposed along what might be termed the leading edge of the bed plate is a barrier 49 having journaled therein a screw 50 supplied with an operating wheel 51. The screw 50 is threadedly related with a leg 52 upstanding from the slide plate and accordingly any rotative action of the operating wheel 51 will result in moving the grinding wheel forwardly or rearwardly.

From the above it will be noted that various changes and alterations may be made to the illustrated and described construction without departing from the spirit of the invention and scope of the appended claims.

I claim:

1. In a centerless grinding device, the combination of, a plate, a curved support carried by said plate and having spaced feed and outlet chutes arranged respectively to receive and discharge cylindrical blanks, a cage carried by said plate and arranged to rotate about an axis coincident with a center of curvature of said support, means carried by said plate for rotating said cage, means on said cage extending into said support and arranged to control movement of said cylindrical blanks along said support, a grinding wheel within the confines of said support and driven at a greater speed than said cage; an axis of said grinding wheel being spaced from said axis of said cage so that as said cylindrical blanks approach said discharge chute the distance between said

grinding wheel and support will gradually decrease, and means for moving said plate toward and away from said grinding wheel.

2. In a centerless grinding device, the combination of, a plate, a curved support mounted on said plate and having spaced feed and outlet chutes arranged respectively to receive and discharge cylindrical blanks, a cage carried by said plate and arranged to rotate about an axis coincident with a center of curvature of said support, fingers carried by said cage extending into confines of said support and arranged to control movement of said cylindrical blanks along said support, a grinding wheel of less diameter than said cage and within the transverse limits of said fingers, said grinding wheel being driven at a speed in excess of said cage rotation, said grinding wheel forming an eccentric pattern with said cage so that the distance between a periphery of said grinding wheel and said support will gradually diminish from said feed chute to said outlet chute, and means for moving said plate toward and away from said grinding wheel.

3. In a centerless grinding device, the combination of, a plate, a stationary support mounted on said plate and having spaced delivery and outlet chutes arranged respectively to receive and discharge a continuous flow of cylindrical blanks, a movable cage carried by said plate and having a plurality of spaced means extending into the confines of said support for controlling movement of said cylindrical blanks through said support, movable grinding means in radial alignment with said cage and support and having a portion only thereof extending into the limits of said support short of said cage means; a periphery of said grinding means gradually approaching a back-up wall of said support as said cylindrical blanks approach said outlet chute so that said cylindrical blanks will bear against said back-up wall as said grinding means profiles said cylindrical blanks, and means for moving said plate toward and away from said grinding means.

4. In a centerless grinding device, the combination of, a plate, a stationary support carried by said plate and having spaced delivery and outlet chutes arranged respectively to receive and discharge a continuous flow of cylindrical blanks, a movable cage spaced from said support and having a plurality of spaced fingers extending into confines of said support for the control of said cylindrical blanks through said support, said movable cage being carried by said plate, movable grinding means having a portion only thereof extending into the limits of said support and arranged to move at a rate greater than the rate of movement of said cage fingers; said grinding means forming an eccentric pattern within said support so that said grinding means will gradually cut into said cylindrical blanks as the latter approach said outlet chute, and means for moving said plate toward and away from said grinding means.

5. In a centerless grinding device, the combination of, a stationary annular support for carrying cylindrical blanks and provided with a delivery chute and a discharge chute, driven means at one side of said support having fingers extending into said support for the control of flow of cylindrical blanks from said delivery chute to said discharge chute, and cutting means driven at a greater speed than said driven means, a single means for moving said support and driven means laterally toward and away from said cutting means, said cutting means being mounted eccentrically on said support.

trically with respect to said annular support so as to urge said cylindrical blanks against said support and gradually profile said cylindrical blanks as the latter approach said discharge chute.

6. In a centerless grinding device, the combination of, a stationary annular support for carrying cylindrical blanks and provided with a delivery chute and a discharge chute, driven means at one side of said support having fingers extending into said support for the control of flow of cylindrical blanks from said delivery chute to said discharge chute, cutting means driven at a greater speed than said driven means, a single means for moving said support and driven means transversely toward and away from said cutting means, said cutting means being mounted eccentrically with respect to said an-

nular support so as to gradually profile said cylindrical blanks as the latter approach said discharge chute; said cutting means being pivotally mounted about an axis spaced from an axis of said cutting means so as to move the latter about an arc toward and away from said support.
